UNITED STATES PATENT OFFICE.

FRED GRAF, OF SOUTH BEND, INDIANA, ASSIGNOR TO AMERICAN FOUNDRY EQUIPMENT COMPANY, OF NEW YORK, N. Y., A CORPORATION OF OHIO.

SAND-CUTTING MACHINE.

Application filed August 17, 1926. Serial No. 129,676.

My invention relates to a sand cutting machine designed to be used in foundries for treating sand used in molding. My invention relates more particularly to a cutting device and the provision of an arrangement which will leave the floor in a cleaner state, eliminating any possibility of side spill and in addition performing a more thorough cutting action in its entire width.

10 Sand cutting and piling machines have been commonly constructed with a series of rotary blades having a general radial disposition. In revolving, these blades cut into the sand a greater or less distance as desired. 15 In machines of the above character a certain amount of sand slides off from the ends of the blades leaving a row of sand on each side of the machines as it moves over the floor.

The present invention provides a sand cutting and piling machine capable of thoroughly cutting the sand and placing it in a ridge or row, eliminating side spill and leaving the floor in a cleaner state. This is accomplished by providing a blade structure comprising a 25 series of generally radial blades for cutting, mixing and piling the sand and a helical blade disposed at each end of the radial blades. The helical blades, in revolving, cut into the sand and force it toward the center 30 of the machine where it is operated upon by the radial blades in the manner above stated.

35 The helical blades, in addition to forcing the sand from the sides of the machine to the central blades and preventing any substantial amount of material from escaping at the sides, serve to thoroughly mix and aerate the sand and insure a more satisfactory and complete operation of the machine.

As the machine constructed in accordance 40 with this invention is passed over the floor the sand is completely mixed, aerated and removed to form a neat center ridge or pile. No ridges of sand are left at the sides which would require re-running the machine with 45 consequent loss of time and expense and the sand is substantially and completely recovered in one operation.

Various other features and advantages of 50 the invention will be obvious from the following particular description of one form of mechanism embodying the invention or from an inspection of the accompanying drawings; and the invention also consists in certain new and novel features of construction

and combination of parts hereinafter set forth and claimed.

In the accompanying drawings I have shown for the purposes of illustration one form of mechanism embodying the invention, in which:

Fig. 1 is a side elevation of the cutting cylinder;

Fig. 2 is a view of the machine incorporating the cutting cylinder;

Fig. 3 is a section on the line 3—3 of Fig. 1; 65

Fig. 4 is a section on the line 4—4 of Fig. 1; and

Fig. 5 is an end view of the cutting cylinder.

In the following description and in the 70 claims, parts will be identified by specific names for convenience, but they are intended to be as generic in their application to similar parts as the art will permit.

Referring to the drawings the machine 75 may be of any type and preferably has a frame mounted on wheels adapted to be run over the floor on which lies the sand to be treated. The cutting cylinder is carried by a shaft 20 rotatably mounted in an adjustable 80 swinging frame 21 which is pivoted to the machine body permitting the cutting cylinder to be raised and lowered with respect to the sand to be treated. The cutting cylinder comprises center members 25 for cutting and 85 mixing the sand, and end members 26 for conveying sand into position where it may be cut and mixed by the center members.

Along the shaft 20 at spaced intervals 90 spiders 30 are mounted so as to be rotatable therewith. Each of these spiders comprises spoke like members 31 connecting the rim 32 to a hub 33 which is rigidly secured to the shaft 20. .

The center cutting and mixing blades 25 95 are mounted on the spiders 30 by means of brackets 35 supported on the rims 32 of the spiders. Each bracket 35 may be of any suitable construction. As shown, it comprises a base 36, an arm 37 and a rib 38. The base 36 of the bracket is slightly curved to conform to the periphery of the rim 32 on which it is mounted.

The arm 37 of the bracket rises at substantially right angles to the base 36, and is shaped so as to conform to the spiral contour of the blade, to which the arm is secured. The rib 38 extends from the base 36 to the upper end

of the arm 37 so as to re-enforce the bracket.

As shown in the drawing the center piling and mixing blades 25 are in two sets 40 and 41, and the cutting blades 25 of each set have 5 a parallel relation to one another and are set lengthwise in a diagonal direction with their width 42 on radial lines. The diagonal arrangement admits of the blades moving the sand transversely of the machine, whereas 10 the radial disposition of the blades enables their edges to radially penetrate the sand, and their broad, flat sides to act as paddles in lifting and tossing the material. The blades 43 of one set 40 are similarly inclined in an option 15 positive direction to the blades 44 of the other set 41, with the result that the material is worked toward the center and ridged in the rear of the machine. The blades have a staggered or alternate arrangement, the blades 43 of one set being located opposite the spaces 20 between the blades 44 of the other set so that the blades of the two sets will alternately and successively act upon the material, and in passing through the latter impart a whirling or vortex motion thereto, thereby rapidly and 25 thoroughly breaking and separating the sand.

The conveyor blades 26 are supported at each end of the shaft by the last two spiders 50 and 51 which are shown spaced apart more 30 widely than are the intermediate spiders 52.

Each conveyor blade 26 is in the form of a helix, and has its extreme ends 54 and 55 secured by means of brackets 53 to the rims 56 and 57 respectively of the last two spiders 35 50 and 51 and has its intermediate helical portion 58 supported by brackets 59 mounted on tie bars 60 connected between the rims 56 and 57 of the spiders 50 and 51. The conveyor blades 26 on either end are of opposite pitch 40 so that when rotated they will draw material in from the ends toward the center.

The number of tie bars 60 may be varied, six being shown by way of illustration in the drawings. These tie bars are shown distributed evenly around the periphery of the spiders 45 50 and 51 and are positioned parallel with respect to the shaft 20 with their ends secured to the outer faces of the rims, 56 and 57.

50 The brackets 65 are similar in construction. Each bracket 65 is substantially T-shaped in form, having its base 66 supported on spider rim 57 or 58 or on one of the tie bars 60 and its stem 67 and head 68 shaped to conform 55 to the spiral face of the conveyor blade 26 to which the bracket may be secured by any suitable means, as by bolts or rivets 69.

In operation the revolving cylinder will 60 operate to convey and sweep the outer portions of the sand to the center cutting and mixing blades, during which action the sand receives an aerating and mixing action.

65 By the construction according to the invention a cutting cylinder is provided which permits the sand to be cut and mixed in a

thorough manner throughout the entire width of the cutting cylinder. The helical conveying blades on either end eliminating any possibility of the sand spilling at either end of the cylinder, and insures the floor being left 70 in a cleaner state.

While I have shown and described and have pointed out in the annexed claims certain novel features of the invention, it will be understood that various omissions, substitutions and changes in the forms and details of the device illustrated and in its operation may be made by those skilled in the art without departing from the spirit of the invention. 75

What is claimed is:

1. In a cutting device for a sand cutting machine, the combination with blades for mixing the sand, of blades for conveying the sand to said mixing blades, means for supporting said mixing blades intermediate said conveying blades, said conveying blades being formed as helices, the pitch of one helix being opposite to that of the other helix to permit the conveying blades to draw sand inwardly from each end toward the mixing blades, said mixing blades being formed in two sets, the blades of each set having a parallel relation to one another and positioned in a diagonal direction with their width on radial lines, the blades of one set being similarly inclined in an opposite direction to the blades of the other set and having a staggered arrangement, the blades of one set being located opposite the spaces between the blades of the other set. 90

2. In combination with a sand cutting machine, a sand treating device comprising a plurality of centrally disposed, diagonally extending, cutting blades and helical blades arranged on each side thereof for conveying sand to said cutting blades. 105

3. A device for treating fine materials comprising a rotatable shaft and a plurality of helical blades attached thereto, the blades on opposite sides of the middle part of said shaft being oppositely inclined and the central blades being of steeper pitch than the end blades. 110

4. A machine for treating fine materials comprising a rotatable member having centrally disposed, diagonally extending cutting and piling blades and helical blades adjacent thereto, and on opposite sides thereof, said helical blades being of opposite pitch whereby fine materials may be conveyed from the ends thereof toward the cutting and piling blades. 120

5. In combination with a sand cutting machine, a rotating sand treating member, a pair of oppositely inclined sets of helical blades disposed on opposite sides of the central portion of said member, said blades being adapted to cut sand and pile the same centrally, and a pair of helical blades dis- 125

posed on opposite sides of said first mentioned blades for conveying material thereto and preventing said material from passing around the ends thereof.

- 5 6. A sand cutting and piling machine including a rotating sand treating member having a plurality of sets of diagonally extending helical blades, said blades being of opposite pitch on opposite sides of said member whereby the material treated thereby may be urged toward the center, the blades on each side of said center being divided into two groups, one of said groups having a comparatively steep pitch and the other of
- 10 15 said groups having a small pitch, said first mentioned group being adapted to pile said

sand and said second mentioned group being adapted to convey sand thereto.

7. In a machine for treating fine materials, a rotating member comprising a plurality of spirally extending blades, said blades being divided into a plurality of groups, the groups on opposite sides of said member being oppositely inclined and the two central groups being of comparatively steep pitch and having the ends overlapping and alternately disposed and the end groups having a comparatively small pitch and being adapted to convey material to said center group.

In testimony whereof I have hereunto set my hand.

FRED GRAF.
